US0D1061523S

(12) **United States Design Patent** (10) **Patent No.:** **US D1,061,523 S**
(45) **Date of Patent:** **** Feb. 11, 2025**

(54) **DISPLAY**

(71) Applicant: **Dell Products L.P.**, Round Rock, TX (US)

(72) Inventors: **Victor C. Cheung**, Singapore (SG); **Sok Hui Khoo**, Singapore (SG)

(73) Assignee: **Dell Products L.P.**, Round Rock, TX (US)

(**) Term: **15 Years**

(21) Appl. No.: **29/849,992**

(22) Filed: **Aug. 16, 2022**

(51) LOC (15) Cl. **14-02**

(52) U.S. Cl.

USPC **D14/374**

(58) **Field of Classification Search**

USPC D14/130, 335-337, 349, 351-352, 371, D14/374-377, 380-389, 900, 902, 126, D14/378-379; D21/324-325, 329, 332, D21/337, 365; D20/10, 41; D18/4.4-4.6, D18/12.3

CPC G09F 13/00; G06Q 20/18; G06F 1/1605; G06F 1/1601

(57) **CLAIM**

The ornamental design for a display as shown and described.

DESCRIPTION

FIG. 1 is a front perspective view of the display comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof; and

FIG. 9 is a bottom rear perspective view thereof.

FIG. 10 is an enlarged detail view of portion 10 in FIG. 6; FIG. 11 is an enlarged detail view of portion 11 in FIG. 9; and,

FIG. 12 is an enlarged detail view of portion 12 in FIG. 9. The even-dash broken line boxes and lead lines, shown in the drawings, represent the extents of the enlarged detail views and form no part of the claimed design. All other even-dash broken lines illustrate portions of the display that form no part of the claimed design.

1 Claim, 12 Drawing Sheets
